United States Patent Office

Des. 185,346
Patented June 2, 1959

185,346

PHOTOGRAPH AND ADDRESS WALLET

Herbert S. Chase, Woodmere, N.Y., assignor to Bernard Cahn Co., Inc., New York, N.Y.

Application April 24, 1958, Serial No. 50,604

Term of patent 14 years

(Cl. D87—3)

I claim:

The ornamental design for a photograph and address wallet, substantially as shown.
